Norman J. Goldstein

ATTORNEY.

UNITED STATES PATENT OFFICE

DAVID J. KELMAN, OF BROOKLYN, NEW YORK

WREATH AND METHOD OF MAKING SAME

Application filed November 18, 1931. Serial No. 575,704.

This invention relates to wreaths and the methods of making the same. It is directed, for example, to wreaths such as used for Christmas decoration and comprising an annular core, having a covering therein, it being an object of my invention to provide an improved covering for the wreath, made of one or more strands, each composed of rayon, cotton, floss or cellophane fibers, and wound about the core to completely cover and ornament the same. In accordance with my invention the separate strands are bunched together and wound about a common spool. The bunched strands are then unwound from the spool and wound about the wreath to form a ribbon-like strip during the winding operation producing a highly attractive coating or cover for the wreath.

A further object of the invention is to provide an economical, simple and efficient method of making a highly attractive, rugged and practical Christmas wreath of the character described.

Other objects of this invention will in part be obvious and in part hereinafter pointed out.

The invention accordingly consists in the features of construction, arrangements of parts which will be exemplified in the construction hereinafter described, combinations of elements, and of which the scope of application will be indicated in the following claims.

In the accompanying drawing, in which is shown one of the various possible embodiments of this invention,

Fig. 1 is a front elevational view illustrating the method of making a Christmas wreath in accordance with my invention;

Fig. 2 is a cross-sectional view taken on line 2-2 of Fig. 1;

Fig. 3 is a perspective view of apparatus employed in carrying out the method illustrating an intermediate step; and

Fig. 4 is a front view of the wreath embodying the invention.

Referring now in detail to the drawing, 10 designates a wreath embodying the invention here shown in the form of a decorative Christmas wreath comprising a core 10a and

a coating or covering 11. The core 10a may be made of an annular piece of cardboard 12 of semi-circular cross-section, and a flat annular ring 13 made of cardboard and attached to the edges of the ring 12 in any suitable manner. The coating 11 may be made of a plurality of bunched strands 15a of rayon, cotton, floss, cellophane or the like fibers of desired color, wound about the core. The method of making the wreath 10 in accordance with my invention, will now be described.

A number of spools 15 on each of which is wound a single strand 15a made up of bunched fibers, are rotatably mounted on pins 16 extending from a support 17. The strand or cord 15a is preferably made of untwisted fibers; that is a number of fibers are merely bunched together to form each strand. For this purpose, rayon or the like artificial fiber is used, since the extremely long fibers are preferable. The ends of the strands are placed together and wound about a spool 18 which is rotated on a shaft 19 by a motor (not shown) or in any other suitable manner. During the winding of the spool 18 the strands 15a are preferably held together by hand or in any other suitable manner so that all the strands, preferably eight in number, are wound together on the spool 18. In winding the strands 15a on spool 18, it will be noted that said strands are not twisted but merely bunched together.

The composite bunched strand 20 on the spool 18 is thereafter wound about the core 10a in any suitable manner, preferably in the manner and with the apparatus illustrated in my co-pending application, Serial No. 575,705 filed the 18th day of November, 1931. As the composite strand 20 is unwound from the spool 18 and wound on the core 10a, said composite strand forms a ribbon-like member and becomes flattened against the core. Since the fibers of the individual strands 15a are not twisted, and since the strands 15a are not twisted when winding the same on the spool 18, the strand 20 unwinds like a ribbon with the strands 15a substantially disposed side by side and flattens against the core, thus producing a highly attractive, practical and

efficient cover for the core. Thus a simple and cheap ribbon-like member which makes a highly attractive substantially sheet-like cover having a sheen, is obtained for winding about the core without the necessity for weaving operation to produce the ribbon. The ribbon-like strand 20 covers a substantial width of the core in each turn thereof about said core, thus decreasing the number of turns necessary for entirely covering the core.

Obviously, after the strand 20 is completely wound about the core, the end thereof is tied or tucked in to prevent unravelling.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing, is to be interpreted as illustrative and not in a limiting sense.

Having thus described my invention, I claim as new and desire to secure by Letters Patent:—

1. The method of making a wreath consisting in bunching a plurality of strands and winding the same onto a single spool, and then unwinding said bunched strands from said spool and winding the same around an annular core to completely cover the same.
2. A wreath comprising a core and a covering therefor comprising a strand made of elongated and untwisted rayon fibers.
3. A wreath comprising an annular core and covering therefor comprising a plurality of strands wound around said core, each strand comprising a plurality of untwisted and elongated fibers.
4. The method of covering an annular core to make a wreath consisting in winding a strand composed of a plurality of bunched untwisted fibers, continuously around said core.

In testimony whereof I affix my signature.

DAVID J. KELMAN.
